United States Patent Office

Des. 195,824
Patented Aug. 6, 1963

195,824

DRAWER KNOB

Norman D. Louis, 136 S. Poinsettia Place,
Los Angeles, Calif.

Filed Sept. 4, 1962, Ser. No. 71,546

Term of patent 14 years

(Cl. D10—8)

FIG. 1.

FIG. 4.

FIG. 2.

FIG. 3.

FIG. 1 is a front elevational view of drawer knob showing my new design;

FIG. 2 is a side elevational view;

FIG. 3 is a bottom plan view; and

FIG. 4 is a fragmentary horizontal, sectional view taken along the line 4—4 in FIG. 1.

I claim:

The ornamental design for drawer knob, as shown.
